ATTORNEY

UNITED STATES PATENT OFFICE.

CHESTER R. COX, OF BERKELEY, CALIFORNIA.

BUILT-IN DISAPPEARING FURNITURE.

Application filed February 18, 1920. Serial No. 359,745.

To all whom it may concern:

Be it known that I, CHESTER R. Cox, a citizen of the United States, residing at Berkeley, in the county of Alameda and 5 State of California, have invented a new and useful Improvement in Built-In Disappearing Furniture, of which the following is a specification.

This invention relates to folding structures and especially to built in disappearing furniture and the like.

The present invention contemplates the use of obtainable wall or partition space where saving of room is desirable as in flats, 15 apartments, dwellings and the like, and has for its object the building in of foldable disappearing furniture such as wall seats, tables, cabinet attachments, ironing boards, etc.

20 Another object of the invention is to provide a novel structure which permits ready extension or folding of furniture of this character and which forms a support for the same, both in folded and in extended 25 position.

Further objects will hereinafter appear.

The invention consists of the parts and the construction, combination and arrangement of parts as hereinafter more fully described and claimed, having reference to the 30 accompanying drawings, in which—

Fig. 1 is a perspective view of a combination cabinet and seat.

Fig. 2 is a perspective view showing the 35 seat in folded position.

Fig. 3 is an enlarged central vertical section of the seat.

Fig. 4 is an enlarged detail view of the 40 flexible connection formed between the seat and one of its supporting members.

Fig. 5 is an enlarged detail sectional view of the inner seat connection.

Fig. 6 is a perspective view of a foldable 45 disappearing shelf.

Fig. 7 is a central vertical section showing the shelf in folded position.

Fig. 8 is a similar section showing the shelf 50 extended.

Fig. 9 is a detail sectional view of the inner end of the shelf.

The present invention is adaptable for various uses and is in the present instance illustrated as applied to a folding disappearing wall seat. The seat here illustrated may be 55 built in cabinet form, such as illustrated in

Figs. 1 and 2, or it may be built in to a wall or partition where space permits.

Fig. 3 illustrates a wall section in which is formed a recess or chamber A. This chamber is enclosed by a casing, consisting of side 60 sections 2 and top and bottom sections 3. The recess is adapted to be closed by a pair of panel sections 4 and 5, which are superposed with relation to each other, and supported one above the other. The upper 65 panel 5 carries a seat section 6, and the lower panel 4 forms a support therefor when the seat is extended as shown. The panels 4 and 5 are connected by a pair of coil springs 7. These springs permit movement of one panel 70 with relation to the other and prevent separation of the same, and to that extent serve the function of a hinge connection.

One of the features of the present invention is to eliminate hardware to as large an 75 extent as possible, hence the reason for the coil spring connection shown at 7. The abutting edges of the panel are grooved as at 8 for the reception of the coil springs 7 and these grooves are sufficiently deep to receive 80 the springs and thereby permits the panels to assume a vertical position when the seat is folded; the ends of the springs being secured to the respective panel sections by 85 screws 9, or other suitable means.

The lower panel 4 is rockably mounted on a cross sill 10, and alignment of the lower end of the panel with relation to the sill is maintained by means of a pair of downwardly extending anchor arms 11, and a facing strip 90 on the front side of the panel as shown in Fig. 3. These arms are secured to opposite sides of the lower panel and project downwardly therefrom. The bottom section 3 of the casing, which is provided for the reception of the seat when folded, is slotted as at 12 to permit the arms 11 to project therethrough, and the lower ends of the arms are notched as at 13 to engage the bottom section 3 which serves as a stop, thereby preventing 95 upward movement of the panel 4 with relation to the cross sill 10 when the lower panel is extended as in Fig. 3.

The panel 4 serves two functions. First that of a closure for the chamber A, and 105 secondly that of a support for the upper panel when in closed position, and for the seat 6 when extended. The rear end of the seat extends into the chamber A and has secured thereto a rounded cross bar 14. 110

(See Figs. 3 and 5.) This cross bar is secured by screws 15, or other suitable means, and it is extended at each end as at 16 to enter a slot 17 formed in each side section 2. These slots serve as a guide for the inner end of the seat and as a support for the inner end of the seat when this is extended, this being accomplished by forming a right angular extension 18 in the slot into which the projecting sections 16 of the cross bar 14 extend when the seat assumes a horizontal position.

The seat is also provided with a back rest 19, which is secured thereto by a pair of bracket members 20. These brackets are disposed one on each side of the seat, and the back section is pivotally attached thereto as at 21. The upper end of the back rest is pivotally connected with a pair of links 22, and these are in turn pivotally attached to the side sections 2 of the chamber as at 23.

With the seat extended as shown in Fig. 3, and if it is desired to fold the same, it is only necessary to grasp the seat of the upper panel 5 at the outer end and to push it inwardly until the projecting sections 16 on the cross bar enter the upper end of the slots 17. The seat is then lifted in an upward direction and its inner end will then be guided by the slots 17 as the cross bar passes downwardly between the same. The panel 4 will at the same time swing inwardly and the back rest 19 downwardly and inwardly, the panels 4 and 5 finally assuming a vertical position and forming a closure for the chamber or recess A, while the seat 6 and the back rest assumes the dotted line positions shown. If it is desired to extend the seat, it is only necessary to grasp the panel by its upper edge and to swing it outwardly. This movement causes forward rocking movement of the panel 4, which is limited when the notched ends of the anchor arms 11 engage the stop member 3. Angular movement of the two panels with relation to each other takes place simultaneously, due to the flexible connection formed by the coil springs 7, and the cross bar will consequently travel upwardly in the slots 17 and will finally pass into the right angular extensions 18 when a slight forward pull is exerted, the back rest of course being guided during this movement by the seat, and secondly by the links 22, and it is therefore automatically positioned whether the seat is extended or folded.

The present structure is adapted for various purposes, for instance, by eliminating the back rest 19, the brackets 20 and the links 22, it becomes possible to employ the seat sections 6 as a table top, or a shelf, or, by extending it, to employ it as an ironing board. The structure may of course be

adapted for other uses not necessarily specified, the important feature of the invention being the structure employed which is exceedingly simple and substantial, due to the fact that hardware and fittings of a similar character are entirely eliminated. The cost of manufacture is also reduced, and the exterior finishing is in no way marred by projecting knobs, handles or hinges.

A slight modification of the invention is shown in Figs. 6, 7, 8 and 9. These views illustrate a shelf which is adapted to be folded or extended. The shelf proper is indicated at 25, and it may serve as a closure for a shaving cabinet, medicine chest or the like. When folded into the position shown in Fig. 7, or it may be swung outward and extended as shown in Figs. 6 and 8 to form a shelf whenever desired. The shelf 25 has a rounded cross bar secured near its inner end as indicated at 26, this cross bar being secured by screws or similar means 27 which extend through the cross bar and enter the shelf 25 on an angle. This is of importance as will hereinafter be described. The cross bar 26 is extended beyond the ends of the shelf and is pivotally mounted in the opposite sides of the cabinet as indicated at 28. The cross bar is at all times partly covered by a false bottom section 29, which first forms a partial covering for the cross bar, and secondly a lock which limits the swinging movement of the shelf when extended, that is by swinging the shelf 25 in a downward direction its inner end, which is extended beyond the cross bar 26, passes under the false bottom section 29 and engages the same, thereby supporting the shelf in a horizontal position and securing it against further movement as shown in Fig. 8.

By referring to Figs. 7 and 8, it will be seen that the forward edge of the false bottom section 29 is rounded to fit the rounded surface of the cross bar. This is important as it forms a snug dust-proof joint between the cross bar and the bottom section 29, and it also serves as means for concealing the screws 27, by which the cross bar is attached to the shelf. This is the reason for inserting the screws on an angle. They are hidden in the position shown in Fig. 7, and they are also hidden by the bottom section 29 when the shelf is extended as in Fig. 8, thereby concealing the screw heads or other fastening means which might be employed.

While certain features are more or less specifically illustrated, I wish it understood that various changes in form and proportion may be resorted to within the scope of the appended claims, similarly that the materials and finish of the several parts employed may be such as the experience and judgment of the manufacturer may dictate or varying uses may demand.

An important feature of the present in-

vention which might be mentioned is the fact that the outer ends of the links 22 are hook-shaped as shown and this permits the links to be disconnected with relation to the back rest 19 and thereby permits the whole structure to be removed with relation to the casing whenever desired. For instance when repairing, inspecting or cleaning the device it is desirable to permit easy removal of the same. This is possible by first unhooking the links, and secondly, swinging the panels into almost vertical position. The projections 11 may then be lifted out of the slots and both panels twisted sideways. This permits the cross bar to be disengaged with relation to the slots and the whole structure to be removed.

Having thus described my invention, what I claim and desire to secure by Letters 20 Patent is—

1. In furniture of the character described the combination with a casing having a chamber or recess formed therein, of a panel forming a closure therefor, a cross-piece 25 forming a support for the lower end of the panel and permitting outward rocking movement of the panel, an anchor arm secured to the panel, and a member with which said arm is engageable during outward 30 movement of the panel to retain the panel on its support and to prevent upward movement of the panel when extended.

2. In furniture of the character described the combination with a casing having a 35 chamber or recess formed therein, of a panel forming a closure therefor, a cross-piece supporting the panel and permitting outward rocking movement of the panel, an anchor arm secured to the panel having a 40 notch formed therein, and means with which the notched portion of the arm is engageable to secure the panel against upward movement when extended and to maintain alignment of said panel with its support.

3. In furniture of the character described the combination with a panel and a support therefor, of means permitting outward rocking movement of the panel upon the support, said means comprising a downwardly 50 projecting arm on the panel, a notch formed in the arm and a member with which the notch in the arm engages, said member and anchor arm securing the panel against upward movement when rocked outwardly 55 upon the support.

4. In furniture of the character described the combination with the lower panel and a support therefor, of means permitting outward rocking movement of the panel upon 60 the support, said means comprising a pair of downwardly extending arms secured one on each side of the panel, and a cross bar with which the lower end of the arms are engageable, said arms being notched to engage the cross bar and to secure the panel

against upward movement when extended and to maintain alignment of said panel with its rocker support.

5. In furniture of the character described the combination with a casing having a recess or chamber formed therein, of a pair of superposed panels forming a closure for the recess, a rocking joint formed between the lower panel and the casing, a rocking connection formed between the upper panel 70 and the lower panel, a cross bar on the inner end of the upper panel, a pair of slots formed in the casing into which the opposite ends of the cross bar extend and whereby the upper panel is guided, a back rest pivotally attached to the inner side of the upper panel and to the lower end thereof, and a pair of links pivotally attached to the casing at one end and to the upper end of the back rest at their opposite ends. 75

6. In furniture of the character described the combination with a casing, of a recess or chamber formed therein, of a pair of superposed panels forming a closure for the recess, a rocker joint formed between the 90 two panels, a rocker joint formed between the lower panel and the casing, said last named rocker joint being formed by rabbetting the edge of the panel to form a projecting exterior portion on the panel outside 95 of the casing, a pair of arms secured to the inner side of the lower panel and at the lower end thereof, said arms and exterior panel portion maintaining alignment between the panel and its rocker bearing support, a notch formed in the lower end of each arm, and a cross member with which they engage when the lower panel is extended. 100

7. In furniture of the character described the combination with a casing having a recess or chamber formed therein, of a pair of superposed panels forming a closure for the recess, a rocking joint formed between the lower panel and the casing, a rocking connection formed between the upper panel and the lower panel, a cross bar on the inner end of the upper panel, a pair of slots formed in the casing into which the opposite ends of the cross bar extend and whereby the upper panel is guided, a back rest pivotally attached to the inner side of the upper panel and to the lower end thereof, a pair of links pivotally attached to the casing at one end and to the upper end of the back rest at their 110 opposite ends, and a right angular extension formed on the upper end of each slot into which the cross bar end is adapted to extend. 115

8. The combination with a recessed casing, of a seat having a foldable back, and a pair of vertically movable flexibly hinged panels, to the upper one of which the seat is secured, said panels being movable to enclose the seat and back within the recess and extensible 125 130

to expose the seat and back in operative position, a pivotal connection formed between the seat and the lower end of the back section, and a pair of links pivotally connected 5 to the upper end of the back section at one end, and pivotally connected to the casing at their other ends.

9. In furniture of the character described, 10 a pair of superposed panels, one panel having an end resting upon the end of the other panel, said ends being recessed to provide projecting portions on opposing sides thereof to form a joint, and a pair of longitudinal aligned grooves formed adjacent said recessed ends, and a flexible and yieldable member having its ends secured at the inner end of each groove thus providing a hinge upon which the panels may be swung toward one another in either direction.

20 10. In furniture of the character described, a pair of superposed panels, one panel having an end resting upon the end of the other panel, said ends being recessed to provide projecting portions on opposing sides thereof to form a joint, and a pair of longitudinal aligned grooves formed adjacent said recessed ends, the grooves of one panel aligned with the grooves of the other panel, and a coil spring for each pair of aligned grooves, having its opposite ends secured to the inner ends of said grooves, thus providing a hinge upon which the panels may be swung toward one another in either direction.

35 11. In furniture of the character described, a pair of superposed panels, the upper panel having an end resting upon an end of the lower panel, said ends being recessed to provide projecting portions on opposite sides thereof, and the outer edge of the recessed portion of one end being rounded to permit free swinging of said panels in one direction and a flexible yield-

able member connecting the recessed ends of the panels, whereby said panels may be 45 swung toward each other in the direction heretofore mentioned.

12. In furniture of the character described, a pair of panel members, the upper panel resting upon the upper end of the lower panel, said ends being recessed to provide a projecting portion on opposing sides thereof to form a joint and longitudinal grooves formed adjacent said recessed ends, a coil spring for each pair of aligned 55 grooves, said springs having their free ends secured near the terminal of the grooves, and a board secured to the side face of one panel and extending over the other panel, said board permitting the panels to swing 60 toward one another in one direction, and at all times concealing the hinge of the panels.

13. In furniture of the character described, the combination with the casing having a recess or chamber formed therein, of a panel adapted to form a closure for the lower portion of the chamber, a rocker joint formed between said panel and the casing, said last named rocker joint being formed 65 by rabbetting the edge of the panel to form a projecting exterior portion on the panel exterior of the casing, and a pair of arms secured to the inner side of the panel adjacent the lower end thereof, said arms and 70 exterior panel portion maintaining alignment between the panel and its rocker bearing 75 support.

In testimony whereof I have hereunto set my hand in the presence of two subscribing 80 witnesses.

CHESTER R. COX.
